CLAIM

The ornamental design for a computed tomographic scanner, as shown and described.

DESCRIPTION

FIG. 1 is a front, top, and right perspective view of the new design of a computed tomographic scanner showing our new design;

FIG. 2 is rear, bottom, and left perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top view thereof; and,

FIG. 8 is a bottom view thereof.

The broken (dashed) lines show portions of the computed tomographic scanner that form no part of the claimed design.
